ABSTRACT OF THE DISCLOSURE

A novel method of providing lateral guidance to floors during their lifting for the erection of buildings, by means of a removable, vertically extended, stiffening structure.

This invention relates to a method of providing lateral guidance to floors during their lifting for the erection of buildings by using a vertically extended structure.

In conventional methods for lifting floors attention was not paid sufficiently to providing lateral stabilization. According to one method, however, the floors are lifted while being guided by constructions remaining as permanent components in the building, as for example elevator shafts and staircases which in such a case are erected prior to the lifting of the floors. According to another method, the guidance is effected by iron stands which are not intended to remain as permanent components in the building but can be placed in the spaces provided to serve for staircases and elevator shafts.

This invention is substantially characterized in that the method comprises a first operation phase wherein a laterally stiffening structure is anchored in a cast base plate and serves as guiding means during the lifting of the basement floor and of one or some more floors until said floors have reached their level of mounting and are supported by vertical building elements, and a second operation phase wherein the structure is separated from the base plate and is secured to the next floor to be lifted with which it follows during its lifting while at the same time being guided by the basement floor and the first floor or, alternatively by the first floors already in position.

This invention relates to a novel method of providing lateral guidance to floors during the erection of building structures. The method essentially comprises forming a base plate, providing a vertically extending guiding and stiffening structure, anchoring the lower end of said stiffening structure in said base plate, forming at least one floor on said base plate with portions thereof engaging the stiffening structure in guiding relationship, sequentially lifting each floor to its final position in the building and positioning substantially vertically extending supporting means intermediate the floors, forming at least one additional floor on the uppermost supported floor with portions engaging the stiffening structure in guiding relationship wherein said stiffening structure is of a length at least equal to the thickness of the floor stack increased by two storey heights, separating the lower end of the stiffening structure from the base plate and attaching the upper end of the stiffening structure to the upper surface of the uppermost of said additional floors and raising the lowermost additional floor into position with the stiffening structure being guided by the previously supported floors.

The method according to the invention will be described in greater detail in the following, reference being had to the accompanying drawings whereon

FIGS. 1—4 show in a schematical manner different operation phases of the method, and

FIGS. 5 and 6 show by way of example some placements of the structure.

2

According to the method of the invention, the first step is to pour in conventional manner a base plate 9 and to pour thereon the basement floor 2a. Prior to the lifting of the latter by jacks in known manner, a first part of a laterally stiffening structure 3 is mounted on the base plate on the foundation, preferably of storey height. The said structure may comprise two separate sections each placed on one of the outer surfaces of the basement floor 2a, or the structure may comprise different parts placed in openings provided in the basement floor 2a as shown in FIG. 5, or it may be a single section disposed directly in the centre of the basement floor as shown in FIG. 6. This structure and these structures respectively may, for example, be iron pillars adapted to take up possible lateral forces in the floors. When the laterally stiffening structure sections are placed at the edges of the floors, iron guides are bolted in the floors to guide the floors along the structure sections.

After the basement floor 2a is lifted by jacks to its level of mounting, forms are made for the future staircases, elevators shafts and/or stiffening walls 6 whereafter these elements are poured. As an alternative, the said elements may be pre-fabricated units to be mounted in their positions. This part of the method is shown in FIG. 1.

The basement floor 2a being fixed in the same manner, a plurality of floors 2b is poured upon the same, whereafter the jacks 1 are placed below the basement floor 2a and provided with extension rods to extend through openings in the basement floor. The jacks and rods press the floor stack upwards by one storey, after the laterally stiffening structure 3, 4 has been lengthened by an additional storey height. The form side which has no contact with the floors 2b at the walls of the stiffening elements, that is staircase walls elevator shaft walls and/or other walls is lifted in connection with the floor lifting in that it is anchored in the floor stack.

After the lifting of the floor stack, the lowermost floor is fixed on bearing elements whereafter laterally stiffening walls 6 are poured a further storey height. The described part of the method constitutes the first operation phase of the method and is carried out according to FIGS. 2 and 3 until the structure comprises the three parts 3, 4 and 5. As appears from the said figures, laterally stiffening walls are poured and inserted respectively at the end of said operation between the base plate 9 and the basement floor 2a as well as between the latter and the first of the floors 2b.

Thereafter follows the second operation phase of the method wherein the structure 3, 4 and 5 is separated from its foundation on the base plate 9 and secured to the uppermost floor 2b of the remaining floor stack, for example by means of a beam 8. Upon lifting the floor stack the structure follows along one storey, as shown in FIG. 4, and is guided by the stiffened part of the building, i.e. both in the basement floor 2a and in the first floor 2b.

The pouring and inserting respectively of laterally stiffening walls 6 is then carried out in the above-described way. As the erection of the building continues, the structure follows along storey by storey until the building is completed. The structure can then be dismantled for use on another building site.

The laterally stiffening structure need not be higher than the thickness of the floor stack increased by two storey heights. The structure may, of course, be higher in cases where it is practical and necessary, for example, to pour the walls one storey later than described above. The structure may also be constructed such, that walls for two storeys can be poured simultaneously, for example for the second and third storey, for the fourth and fifth storey, and so on. The same constructions for lateral stiffening may also be used even if no permanent walls are poured before the floors were lifted to full height in

all storeys. In such a case, however, the laterally stiffening constructions must be made substantially stronger than otherwise required.

What I claim is:

1. A method of providing lateral guidance to floors during their lifting for the erection of buildings comprising providing a vertically extending guiding and stiffening structure, forming a base plate, anchoring the lower end of said stiffening structure in said base plate, forming at least one floor on said base plate with portions engaging said structure in guiding relationship, sequentially lifting floor to its final position in the building construction and positioning substantially vertically extending supporting means intermediate said floors, forming at least one additional floor on the uppermost supported floor with portions engaging said stiffening structure in guiding relationship, said stiffening structure being of a length at least equal to the thickness of the floor stack increased by two storey heights, separating said lower end of said stiffening structure from said base plate and attaching the upper end of said stiffening structure to the upper surface of the uppermost of said additional floors, and raising the lowermost additional floor into position with said stiffening structure being guided by the previously supported floors.

2. A method in accordance with claim 1 wherein a plurality of additional floors are formed on said uppermost supported floor, further including repeating the steps of positioning substantially vertically extending supporting means intermediate the uppermost supported floor and the lowermost unsupported floor, and raising the next lowermost additional floor into position with said stiffening structure being guided by at least the uppermost supported floor.

3. A method in accordance with claim 1 wherein after said base plate is formed two floors are cast thereon with portions engaging said stiffening structure in guiding relationship, said stiffening structure being at least equal to the distance between said base plate and the upper of said two floors in the final position of the same in said building construction plus the thickness of said additional floors, and said stiffening structure being guided by at least two previously supported floors during the lifting of said additional floors.

4. A method in accordance with claim 1 wherein after said base plate is formed, one floor is cast thereon with portions engaging said stiffening structure, lifting said one

floor to its final position in the building construction, positioning substantially vertically extending supporting means intermediate said base plate and said one floor, casting a plurality of additional floors on said one floor with portions engaging said structure, adding an additional section to said stiffening structure to form an extended stiffening structure, said extended stiffening structure being of a length at least equal to the thickness of the floor stack increased by two storey heights, lifting said additional floors to locate said first additional floor in its final position in the building construction, positioning substantially vertically extending supporting means intermediate said one floor and said first additional floor, separating said lower end of said extended stiffening structure from said base plate and attaching the upper end of said additional stiffening structure to the upper surface of the uppermost of said additional floors and lifting said additional floors into their final position in the building construction one storey at a time in the same manner with said extended stiffening structure being guided by at least the last two previously supported floors.

5. A method in accordance with claim 1 wherein said supporting means are walls successively cast in situ.

6. A method in accordance with claim 1 wherein said supporting means are staircases successively cast in situ.

7. A method in accordance with claim 1 wherein said supporting means are prefabricated units.

8. A method in accordance with claim 1 wherein said stiffening structure includes two sections placed on the opposite outer edges of the floors.

9. A method in accordance with claim 1 wherein said stiffening structure includes at least one section placed in openings defined in the floors.
